UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

TYPE SETTING AND DISTRIBUTING MACHINE.

1,197,848.

Specification of Letters Patent. Patented Sept. 12, 1916.

Application filed October 14, 1914. Serial No. 866,695.

To all whom it may concern.

Be it known that I, HENRY C. OSBORN, a citizen of the United States, residing at Cleveland, in the county of Cuyahoga and State of Ohio, have invented a certain new and useful Improvement in Type Setting and Distributing Machines, of which the following is a full, clear, and exact description, reference being had to the accompanying drawings.

The object of this invention is to provide a simple, efficient and rapidly operating machine for the assemblage and distribution of type, under the control of a key-board.

My invention is well adapted for use with short groove type, such as are employed on the multigraph, though it is not limited thereto.

The invention in its preferred embodiment has an upper bank or type case at the lower end of which type are assembled and a lower bank or case into the upper end of which they are distributed, an intermediate gate controlling the discharge from or admission to the respective cases. These cases are interchangeable so that, when the upper case becomes nearly empty and the lower type case correspondingly full, they are transposed and type is removed from the nearly full case and distributed into the more nearly empty one. By means of these interchangeable type cases I provide a gravity assemblage and a gravity distribution system. There are preferably provided pairs of upper and lower type banks facing each other, and between such pairs (adjacent to the line of division between the upper and lower cases) is placed an endless carrier adapted to receive type from either of the upper cases when composing, or carry it to either of the lower cases, in distributing.

Important features of the present invention reside in the surmounting cases with the intermediate assemblage and distribution mechanism, also in the idea of cases facing each other with a common endless carrier between them.

Another feature of the invention comprises the employment of upper and lower case characters in the respective banks and a suitable shift mechanism for moving such banks laterally so that a single-character key-board may co-act therewith.

The gates at the lower ends of assemblage channels are preferably oscillating slotted heads, which may be turned to present their slots in a vertical direction to aline with individual channels to receive type from the upper case and then turned into a horizontal position to aline with each other and provide a continuous discharge channel. This feature is shown and claimed in my co-pending application No. 786,447, filed August 25, 1913. Provision for using the same oscillatory heads for distributing, is included in the present invention.

Other features of the invention will appear from the following more detailed description.

In the drawings, Figure 1 is a front elevation of my machine; Fig. 2 is an end elevation looking from the right hand end of the machine; Fig. 3 is a vertical transverse section looking from the opposite direction to Fig. 2, the planes of the section being indicated by the offset line 3—3 of Fig. 1; Fig. 4 is a sectional plan of the machine substantially on the offset line 4—4 of Fig. 3; Fig. 5 is a sectional front elevation, being a section indicated by the offset line 5—5 in Fig. 4. The remaining views are details principally on a scale three times that of the preceding figures. Figs. 6 and 7 are elevations substantially on the line 6—6 of Fig. 2, Fig. 6 looking toward the left and Fig. 7 toward the right; Fig. 8 is a cross section on the line 8—8 of Fig. 6; Fig. 9 is a detail of the mechanism for controlling the alinement of the banks, being an enlargement of the same mechanism appearing near the bottom of Fig. 1; Fig. 10 is a bottom plan of the mechanism shown in Fig. 9; Fig. 11 is a perspective view of the removable holding trough at the bottom of the type bed; Fig. 12 is a view of the block for holding the banks in place, being substantially a horizontal section on the line 12—12 of Fig. 3; Figs. 13 to 16 are diagrammatic details of the oscillatory gate and its operating bar; Fig. 17 is a perspective of the gate.

As shown in the drawings, the frame of my machine comprises a suitable bed 1, from which rises a transverse vertical plate 2 and two longitudinal vertical plates 3 and 4 parallel with each other and some distance apart, and (directly above the latter) two other longitudinal plates 5 and 6, separated

from the lower plates by horizontal frame bars 7 and 8. The plates 3 and 4 are shown as secured to the bed near their lower ends by ears and cap screws 9. The upper and 5 lower plates are secured together by bolts passing through the intermediate bars 7 and 8, and these bars are secured at their right hand end to the transverse plate 2. A suitable cross bar 11 at the top of the machine 10 braces the plates 5 and 6. The longitudinal stationary frame plates, 3, 4, 5 and 6 are cut away for lightness, as shown, and each is provided with four horizontal guideways, two facing upwardly and two downwardly. 15 The guideways which face upwardly near the bottom of the respective plates are indicated by the numerals 15 and 16 and those near the top of the plates which face downwardly are indicated by 17 and 18. In the form 20 shown, each of these guideways is made V-shaped to form a portion of a ball-race. Slidably mounted in the respective guideways are four vertical plates, designated 21 to 24 inclusive. These plates stand adjacent 25 to the inner faces of the corresponding vertical frame plates and are each provided on their outer sides with members which have horizontally extending grooved faces completing the ball-races referred to. The 30 downwardly facing members on the lower and upper plates are designated 28 and 29 respectively; the upwardly facing members are designated 30 and 31.

33 indicates one or more balls in the 35 various raceways referred to.

To enable the convenient assemblage and adjustment of the ball bearings referred to, I find it convenient to make the lower members 28 and 29 on the shiftable plates 21—24 40 rigid with the plates, while the upper members 30 and 31 are movable blocks, held in place by screws 40 (Fig. 1) passing loosely through the blocks into the plates and there being set screws 41 mounted in ribs on the 45 plates and bearing against the lower edge of the blocks. The plates 21—24 referred to carry the respective type banks, as herein-after explained, and these plates are made easily movable on the frame plates by the 50 ball bearings described, to enable the lateral shifting of the banks a distance corresponding to the width of a single channel to enable two channels (one for upper case characters and one for lower case characters) to co- 55 operate at will with a single gate controlled by a single finger key. Accordingly, the movement of the plates 21—24 is comparatively slight. This movement is accurately limited by means of set screws 37 and 38 60 mounted in inwardly extending lips near the opposite ends of the respective frame plates and bearing against the edges of the shiftable plates.

The different banks for holding type consist of parallel rails 45 mounted on upper

and lower cross bars 46 and 47 which are slidably dove-tailed in the shiftable plates. This construction enables any bank to be drawn out of its supporting plate edgewise. When in place the banks are locked by suitable means, as, for example, bolts 49 which are mounted in the bosses 28 and 29 and are pressed into cross bars 46 by springs 48 (Fig. 12). The bolts have their outer ends turned at an angle, as shown in Fig. 1, enabling them to be conveniently drawn out and turned past a hump on the boss to release the corresponding bank.

In the particular embodiment shown, the machine is adapted for operation with short 70 type grooved on its opposite sides and the bars of each bank are of an I-shape in cross section, thus loosely confining the type, as indicated in Fig. 12. The type, which also appear in Figs. 2, 3 and 5, are designated 80 50. These type, being loosely confined in the vertical channels, drop by gravity to the bottom of the channel, or as near thereto as type below them permits. Means are provided for supporting type in the various 90 channels. In the case of the upper type cases, the gates mounted in the bars 7 and 8, as hereinafter explained, support the type. In the lower type cases the type are supported by horizontal trough-shaped bars 52, 95 (Figs. 3 and 11) which embrace the lower ends of the channel bars and are held in place by having inwardly turned flanges 53 occupying notches 54 in the bars. Fig. 3 shows the lower type cases so equipped, and 100 these type cases when released by the bolts 49, may be drawn out edgewise with the supports 52 and thus retain their type. When the upper cases are drawn out a trough-bar similar to the bar 52 is placed opposite the 105 lower edge of the bank so that alined notches 54 on the rear of the channel bars slide over the flange 53 and thus support the trough-bars on the bank and retain the type from dropping out.

110 It is to be understood that, when the upper banks from which the type are assembled become more or less nearly empty and the lower banks into which the type are distributed become correspondingly nearly 115 full, the upper and lower banks are interchanged. Thus, for example, the lower bank is drawn out edgewise and stood aside, the upper bank is then drawn out edgewise onto a temporarily held trough bar 52 and then such bank, so equipped, is shoved into the place of the lower bank; then the former lower bank is shoved into the seat for the upper bank, and, in doing so the bank slides off of the corresponding trough bar 120 52, which is set aside until another interchange is made.

125 I will now describe the means by which the finger keys control the assemblage from the upper banks and distribution into the 130

lower banks. Mounted in the horizontal frame bars 7 and 8 are a series of oscillatory gates 60 and 61, one for every two channels of the type banks above the gates 5 or below the gates; that is to say, each gate is designed to effect the assemblage from two channels above it and the distribution into two channels below it, by reason of a shift mechanism which, when desired, 10 shifts those banks laterally the distance of one channel. The type gate (shown in Figs. 3, 4, 5, and 13 to 17) comprises a cylindrical shank 62 journaled in the corresponding frame bar and an enlarged cylindrical head 63, on the inner face of the bar and standing directly beneath the corresponding type bank. The head 63 is provided with a normally transverse slot or groove 64 and a short normally vertical slot or 20 notch 67 at the bottom. These transverse grooves normally all align, as shown in Fig. 5, to make a channel for discharging the released type or receiving the type to be distributed.

25 To assemble type, the gates corresponding to the desired channels are successively given a quarter turn, making their grooves vertical, as shown in the case of the left hand gate in Fig. 5. When so turned the column 30 of type (which are piled on their sides) directly above the gate drops by gravity until the lowermost type is within the gate. The column is stopped in this position by such lowermost type engaging and resting 35 on the horizontal toothed plate 65 (Figs. 3 and 4). Then the gate is returned to its original position, whereby the type is turned a quarter way around, passing through the notch between the teeth of the 40 plate 65, and stands with its character upright opposite a continuous channel of grooves across the machine, by which channel the type may be shoved, by suitable means, into an assemblage receiver. To distribute type the gates are similarly given a 45 quarter turn (left hand gate, Fig. 5) and the shoulder at the end of the notch 67 acts as a stop. Fig. 5 shows the machine in its distributing position and with the channels 50 of the upper bank out of registration with the gates. Mechanism hereinafter described, is provided for shifting the upper type cases (simultaneously with other changes to convert the machine from distribution to 55 assemblage, and vice versa) so that during 60 assemblage the channels of the upper banks align with the axes of the gates. To rock the type gates a quarter turn and back by a depression of the finger key, I prefer to 65 use a very simple but peculiarly formed bar connecting the key levers with the shanks of the type gates and acting on different shoulders thereof when the levers are depressed or returned to normal position. 70 This operating device is claimed in my

prior application referred to. It is shown herein in Figs. 3, 4, and 13 to 17.

Figs. 3 and 4 show substantially a standard or Remington keyboard, having the ordinary upper and lower case characters on 75 single keys, as indicated at 70. The levers of these keys are arranged in two sets, the first set 72 resting on the stationary pivot bar 73 and extending beneath the rear cases, and the other set 75 resting on the pivot 75 bar 76 and extending beneath the operating bars of the forward cases. The operating bars for the respective gates are designated 78. They rest at their lower ends on the 80 respective levers and are normally in their lowermost position by reason of their weight assisted by a spring. The upper ends of the operating bars 78 extend alongside of the shanks of the gates 60. These shanks are preferably made tubular and across each 85 shank are notches, at right angles to each other, which provide two pairs of shoulders 81, 82, 83 and 84. Each bar has an upward projection 85 adapted to stand below and shove upwardly on the shoulder 81, and 90 it has a downward projection 86 adapted to overhang and shove downwardly on the shoulder 84. Normally, the bars stand in their lowermost positions with the side face of the portion 86 engaging the vertical surfaces 83 and 84 and the projection 85 directly below the horizontal surface 81. The depression of any key raises its corresponding bar, and this carries the projection 86 upward to idle position and causes the projection 85 to shove upwardly on the shoulder 81, thus giving the shank a quarter turn. In this position the projection 85 engages 95 the now vertical surfaces 81 and 82 and holds the gate with its groove 64 vertical. 100 When the key is released the bar 78 descends, restoring the key lever while the projection 86 acts on the shoulder 84 and turns the gate back to normal position.

The keyboard of this machine is provided 110 with the usual standard space bar 88 mounted on two levers 89. These levers are shown as pivotally mounted on the rod 73, the left hand lever 89 being counter-balanced by the spring 90, while the right hand lever 115 89 extends beneath and acts on a regular upright bar 78 which operates a regular gate coacting with channels which carry space type, *i. e.*, type bodies without characters.

120 As heretofore stated, each key of the keyboard corresponds to both an upper and lower case character and the type banks are shifted the distance of a single channel, when the other of such characters is desired. As explained, this shifting is accomplished by moving the supporting plates 21-24 against the action of the spring 93 interposed between a lug 94 (on the plates 125 21-24) and the shoulder of a cutaway por- 130

tion 91 (in the plates 3-6). This movement is effected by means of rock arms 100 and 101 which are mounted on rock shafts 102 and 103, and carry rollers 104 and 105 bearing against the edge of the respective plates 23, 24 and 21, 22. The rock shafts 102 and 103 are rocked by links 106 and 107 connected with rock arms 108 and 109 on the respective rock shafts. The links 106 and 107 are connected by suitable mechanism (changeable for assemblage or distribution, as presently described) with shift keys 110 and 111. The shift keys are designed to be operated in the usual manner of the standard keyboard; that is to say, the left hand key 110, when depressed and held down, will effect the shifting, but is not designed to remain depressed, whereas the right hand key, which also effects the shifting, may lock itself in the down position but is released by the depression of the key 110. In accomplishing this, the respective levers 114 and 112 are loose on a rock shaft 113 (the rocking of which effects the shifting as hereinafter explained) and each lever stands above a rock arm 115 rigid on the shaft. Accordingly, the downward movement of either finger key rocks the shaft. To retain the shift lever 112 in its lowermost position when it is depressed, I provide a catch 150 (Fig. 3) which is adapted to hook over a pin 151 on the shift lever. The catch is provided with a beveled nose, so that when the lever is depressed the catch is forced from beneath the pin, after which the catch springs over the pin and retains the lever. As shown in Fig. 3, 152 indicates the spring for this purpose, which is connected to a rock arm 153 on a rock shaft 154 with which the catch is rigidly connected. The rock arm 153 is located directly beneath the other shift lever 114. Accordingly, whenever the right hand shift lever is depressed it stays down, insuring upper case characters, until the left hand lever is depressed, which releases the right hand lever, and both levers, on removal of the pressure on the left hand lever, return to normal position. For a few upper case characters, it is more convenient to depress the left hand key and hold it depressed by finger pressure. The means by which the rocking of the shaft 113 effects the shifting includes a rock arm 117 rigid on the shaft, extending forwardly and provided with a yoke plate 118 which extends over hooked ends on the rods 106 and 107.

Assuming that the machine is in use as a composer, the rod 106 is the one under consideration, for the lower cases and their rod 107 are, at such time, idle. From a reference to Figs. 1 and 9, which show the parts in this position, it will be seen that the rod 106 has its hooked end 120 standing directly beneath a downward lug 121 of the yoke plate, while the hooked end 124 of the rod 107 is beneath a recess 125 of the yoke plate. Accordingly, when the shift lever rocks the shaft 113, this draws down on the rod 106 but has no action on the rod 107 on account of the recess 125 above its end. This provides for shifting the upper case in composing. When distributing, the rod 107 is the one to be shifted by the key, and to accomplish this the two rods 106 and 107, when the machine is converted from a composer to a distributer, are moved laterally of their lower ends so that the hooked end 124 of the rod 107 comes beneath the lug 121 in the position occupied by the end 120 in Fig. 9 and the hooked end 120 comes into the position shown in dotted lines in Fig. 9, which is beneath the recess 126. In such position the rocking of the shift affects only the rod 107.

As heretofore explained, when the machine is distributing, it is necessary to shift the upper cases slightly out of their normal position to prevent their channels registering with any vertical grooves in the gates, and, to effect this, I provide a stationary inclined cam 145, which is secured to a boss on the under side of the bed plate and presents an inclined edge adapted to engage the hooked end 120 of the rod 106 when it is shifted to idle position, and during such movement cams that end downwardly into the position shown in dotted lines in Fig. 9. This shifts the upper banks a fraction of the distance between channel centers and holds the upper banks idle, preventing type being discharged therefrom while the machine is a distributer.

To change the position of the shift rods 106, 107 from composing to distributing, and vice versa, I provide a sliding bar 130 (Figs. 9 and 10), which has notches 131 and 132 occupied by the respective rods 107 and 106. The bar 130 is supported by screws 135 passing through slots 136 into bosses 137 on the under side of the bed plate 1. To shift the bar 130 lengthwise I provide a rock arm 140 projecting from a rock shaft 141 and shown as having a ball head occupying a round hole in the bar 130. This rock shaft is mounted in the bed of the machine and has on its forward end a rigid arm 143 which is provided with a knob 144. This knob is mounted on a bolt 145 slidably occupying the arm 143 and pressed inwardly by a spring 146 and adapted to seat in either of two holes 148 or 149 in the front of the bed, as shown best in Figs. 1 and 2. Accordingly, to change the shift mechanism from composing to distributing, and vice versa, it is only necessary to pull outwardly on the knob 144 and move the arm to its other position, allowing the knob lock to seat. In addition to the shift, other changes are necessary when the machine is converted

from composing to distributing, and I effect these changes by means of the same rock shaft 141, which is extended through the bed of the machine, as shown in Fig. 2 and 5 connected at its rear end with other mechanism, hereinafter described.

From the foregoing description the manner of assembling type in the horizontal channel provided by alined grooves of the 10 gates, and for discharging the type reaching a gate through said grooves, will be apparent. I will now describe the conveying means for carrying the assembled type from its gate, or the type to be distributed to the 15 gate.

Secured to the transverse frame plate 2 is a bracket 160 which has a horizontal trough-like portion 161, best shown in Figs. 3 and 4. This trough is divided by a pair 20 of longitudinal partitions 163 into an elongated annular passageway. In this passageway is an endless belt 170 which is stretched about a pair of sheaves 171 and 172. Secured to the belt is a suitable projection 174 25 adapted to carry the type along the channel provided by the alined grooves of the heads as the belt travels. When composing, the belt travels in the right hand direction (looking down in Fig. 4) and this carries 30 the type from the front upper bank of cases to the left, and from the rear upper bank of cases to the right. At the left hand end of the machine a horizontal U-shaped split tube 176 provides a channel which alines with 35 the grooves in the two sets of heads; while at the right hand end of the rear channel of grooves is a straight receiving channel 180. Accordingly, type from the rear bank, released in composing, are carried directly to 40 the right into the channel 180, while type from the front bank are carried to the left and around the U-shaped trackway 176, and then through the alined grooves at the rear into the same channel 180. It is to be un- 45 derstood that the belt is driven fast enough so that type may be carried from the right hand gate of the front bank around the left hand end of the machine and into the channel 180 before a subsequent key will 50 be operated to discharge type at any other point of the belt. Accordingly, there is no transposition of characters, whatever the order of their release. The characters received in composing in the channel 180 pass 55 continuously along that channel in composed alinement, through a channel 191 in a head 190 (used in distributing but stationary in composing) into a removable tube 182. The outer end of the tube is sup- 60 ported by a bracket 185 extending upwardly from the end of the bed. When a line has been thus composed in the tube 182 it is slid lengthwise sufficient to clear its left hand end from the frame part holding it and then 65 swung slightly and drawn out toward the

left from the holder at the other end, and is thus in condition to transfer the line to any suitable printing device—suitable stops if desired being clipped around the tube or sprung into its slot to retain the line during 70 transference.

In distributing type a line thereof is placed in the tube 182 and that tube is put in the same position it occupies in composing. The direction of the movement of the 75 belt, however, is changed so that it can carry type from the channel 180 through the channel of alined grooves, and, if necessary, around the U-shaped track at the end into the second channel of grooves, until it is 80 stopped by coming into a head which has been turned on its axis, whereupon, when such head is returned to normal position, the type is swung downwardly and drops by gravity into the proper channel. To accom- 85 plish the stoppage at the proper point the operator simply presses the key corresponding to the character about to be engaged by the belt. After such stopping the belt is again reversed and travels back into posi- 90 tion for another type.

The conveying belt, it will be seen, has a continuous travel in composing but a reciprocation in distributing. The driving mechanism for this will be hereinafter described. It should be noted at this point that the belt is loose enough on its pulleys 95 so that it may slip whenever the type travel is stopped in either distribution or assem- blage.

In order that the type being assembled shall stand right-side-up in the tube 182 it is necessary when in the upper bank, that they lie on that side which is on the left of one facing the character. As the lower 105 cases, when filled, are transposed and become upper cases it is necessary that the type lie on the same side in the lower cases, but, as the distributing movement of the gates turns the vertical faced type onto 110 their right sides it is necessary to turn them up-side-down before distribution. It is desirable, however, to have them right-side-up when they are read by the operator who depresses the keys. To provide for this contingency I insert a turn-table between the tube 182 and the channel 180, which, though idle during composing, operates during distribution to take the type received from the tube and turn it half way around 115 for discharge into the channel 180. This turn-table is designated 190 in Figs. 5 and 8 and consists of a circular block having a diametric groove 191 adapted to carry type and aline with the channel 180 and the tube 182. This block seats in a corresponding recess in a portion 194 of the transverse plate 2. During composing the turn-table is stationary and, as heretofore explained, the type pass directly through the groove 120 125 130

191. During distribution a guide plate 196, having its lower portion semi-circular and of a radius a type-width less than that of the turn-table, is lowered into the position 5 where its semi-circular lower end is concentric with the lower half of the turn-table. This guide plate thereafter makes a stop for the type; wherefore, by rotating the turn-table a half turn clockwise (Fig. 5) 10 the type is carried from the right hand side of the guide plate to the left hand side and inverted in doing so. Movement is communicated to the turn-table 190 by the shaft 200 on which it is rigid and which 15 is journaled in bearings in the frame plate 2 and carries a sheave 202 (Figs. 2 and 4) loose on the shaft but frictionally held against independent turning by reason of a disk 203 pressed by an adjustable spring 204. A belt 205 about the sheave leads to 20 a source of constant power, which is shown as a sheave 207 on the armature shaft 208 of the motor 209. During assemblage the belt is slack enough to be idle, but, at the 25 time of distribution, a belt tightener bears against the belt and causes it to communicate movement to the sheave 202.

The belt tightener referred to comprises 30 a sheave 210 on an arm 211 which is loose on a rock shaft 213. Rigid on this rock shaft 213 is an arm 215 which has an extension lying behind the arm 211 and provided with a set screw 216 adapted to engage that arm. The arm 215 is connected by a 35 rod 220 with a rock arm 221 on the rear end of the rock shaft 141, which, as heretofore explained, is operated by the arm 143 whenever the machine is changed from the composer to a distributor. In the distributing 40 position, which is that shown in Fig. 5, the arm 143 is in its lowermost position and the shaft 141 has been rocked clockwise, which has pulled down on the rod 220 and thereby forced the set screw 216 against the arm 211 to tighten the belt 205. The 45 same movement lowers the turn-table guide 196 by means of the bar 222 connected by the arm 223 with the guide 196, and at its lower end connected to the rock arm 224 on the shaft 213.

To control the rotation of the turn-table shaft in successive turns of a half rotation each, this shaft is provided with a collar 225 (Figs. 2, 4 and 7) which has diametrically opposite notches, either of which is engaged by the nose of a double-armed latch 227, which is pivoted on a stationary boss 228 of the frame plate 2 and has its other arm extending beneath the shoulder 55 226 of a bar 229. The latter bar extends in an upright direction and is pivoted at 230 on a rock arm 231 rigid on a rock shaft 234. The shaft 234, as presently explained, is rocked clockwise (Figs. 1 and 7) whenever 60 a key is depressed, and during dis-

tribution movement is thus conveyed to the latch 227 (idle during assemblage) to release the turn-table shaft.

Directly above the two sets of vertical operating bars 78 are two universal bars 70 95 and 96, each consisting of a plate extending inwardly from a rod 97, which is pivoted between studs 98 carried by the frame of the machine. Bearing downwardly on the two universal bars are rock arms projecting from the rock shaft 234. The rock arm extending over the universal bar 96 is conveniently made by extending the arm 231 on the left side of its pivot, as shown at 251 (Fig. 7) and providing it with a set screw 250. The arm connecting on the universal bar 95 is shown as the left hand portion of a lever 235 on the forward end of the rock shaft 234, this left hand portion being provided with a ball head bearing on the universal bar. The right hand arm of this lever 235 is provided with a set screw 255 which bears downwardly on a vertically 85 256 pressed upwardly by a helical spring 257. This spring accordingly 90 tends to rock the shaft 234 contra-clockwise and thus performs the double function of raising the bar 229, into position to release the turn-table, and of assisting gravity in depressing the operating bars 78 when the 95 pressure on the finger keys is removed.

It will be seen that whenever one of the bars 78 is raised the shaft 234 is rocked, and that during distribution this withdraws the latch 227 from the head 225 and allows the 100 turn-table to rotate. In order that the notched head 225 may remain locked during assemblage, I provide mechanism which withdraws the bar 229, when the machine is set for assembling, so that the movement of 105 this bar will not cause it to engage the latch 227. This withdrawal is accomplished by a link 240 which hooks around the lower end of the bar 229 and has its other end pivotally connected at 241 to the rock arm 110 242 rigid on the shaft 213, which, as above explained, is turned by the arm 143 whenever the machine is changed from composing to distributing.

Fig. 7 shows the mechanism just described 115 in distributing position, the bar 229 being forced to the right by a spring 245. When this bar is depressed in this position it shoves downwardly on the latch lever 227 for a sufficient distance to release its other 120 end from the notched head 225 and then a cam surface 247 on the bar engages a hub 248 of a cam on the shaft 200 and thereby forces itself to the left to clear the lever 227, whereupon the other end of that lever 125 swings downwardly (being heavier for that purpose) to be in position to engage the other shoulder of the collar on its next half rotation.

Whenever a key is depressed, the univer- 130

sal bar mechanism, above described, depresses the slideable rod 256. Rigid on this rod is an arm 259, and when the machine is set for composing, the rod is turned so that 5 this arm stands above the forward end of a lever 260 (Figs. 2 and 4) the rear end of which is connected with a rocking escapement 261. Thus, in assembling, the depression of a key causes the forward arm 10 262 of the escapement to be projected into the path of the stop 174 on the belt while the rear arm 263, which normally restrains the belt, is withdrawn. When the finger key which caused the operation described, 15 is returned to normal position the rising of the rod 256 oppositely rocks the escapement and releases the forward arm thereof, which releases the belt and allows it to travel until the stop thereon again engages 20 the rear arm of the escapement. As the depression of a key turns the gate, and the raising of the key releases the escapement, it will be seen that before the belt is released the type is necessarily turned down 25 by the turning gate, so that it is in position to be engaged by the belt and is carried thereby into the channel 180. Any sticking of the oscillatory gates, should any accidentally happen, would simply hold the 30 corresponding universal bar elevated and prevent the return of the rod 256, which would prevent the release of the belt by the escapement.

In distributing type the movement of the 35 transporting belt, instead of being continuous, is reciprocatory. It normally stands with its stop 174 in front of the rear arm 263 of the escapement. In distributing, the active movement of the belt is opposite to that of composing, and thus moves the stop away from the escapement and carries the type along until stopped by the type coming into a positioned gate. Then the movement of the belt is reversed (that 40 is given the movement it has in composing) to carry it back to stopped position. To effect the reciprocating movement of the belt the rod 256 which, as heretofore described, moves up and down to operate the 45 escapement in assembling, is given a quarter turn, which throws the arm 259 (which, in composing, lies above the lever 260) out of registration with the lever 260, and throws an otherwise idle arm 271 on the rod 50 into registration with a lever 272. This lever carries a roller 273 engaging the head 274 of a spool 275, (Figs. 1 and 2), which is splined on a shaft 276 and slideable thereon. The spool is provided with another 55 head 277, and between these heads, revolving in a plane at right angles to them, is a disk 280 on the continuously rotating armature shaft 208. During assemblage the head 273 is in engagement with the disk 60 280 and the latter clears the head 277 and

this results in rotating the shaft 276 in a clockwise direction, giving a continuous travel to the belt in the proper direction. Fig. 2 shows the machine set for assembling, and in this position the spool is held 70 in its lowermost position by a spring 279. It will be seen that, by operating the lever 272 and thereby shifting the spool 275, the belt may be caused to travel in either direction, as desired. In distributing, the depression of the forward end of the arm 272, by the arm 271 on the rod 256, whenever a key is depressed, raises the spool against the action of the spring 279 so that the lower head 277 of the spool engages the 80 disk 280, reversing the direction of rotation of the shaft 276, and hence of the belt. This carries the type into the proper gate. When the depressed key returns to normal position the gate turns the type down, 85 as heretofore described, and the rising rod 256 releases the spool so that the head 273 again engages the disk 280 and the belt is returned to starting position. The quarter-turn of the rod 256 referred to, is accomplished automatically whenever the machine is set for distribution, by means of a bell-crank extension 285 of the arm 259, which is connected by a link 286 with an arm 287 on the rock shaft 213, heretofore referred to. 90

The description of the operation of distribution, above given, presupposes that type are supplied continuously to the right hand side of the turn-table 190. To so feed the 100 type I provide a bar 290 (Figs. 1, 4, 6 and 8) carried by the frame plate 2 and the bracket arm 185, and slideable on this bar, a block 291 which carries an arm 292, the upper end of which extends along the face of the tube 182, 105 and, by being moved, is adapted to feed the type. To move the block 291 step by step, I provide on the shaft 200, which carries the turn-table, a cam 294, the hub of which has heretofore been referred to as 248. This cam 110 acts on the roller 295 of a lever 296, the other end of which engages and reciprocates a ratchet rack 297, with which coacts a pawl 298 carried by the block 291. Suitable springs act on the various parts to hold them 115 in proper position. In composing, the arm 292 is swung by means of a handle 299 away from the type and this same movement causes the lower end 293 of the lever 292 to raise the right hand portion of the pawl 298 120 to free it from the rock bar.

It will be seen from the above description that it is an extremely simple matter to change the machine from a composer to a distributor, and vice versa. If the machine 125 is composing, the lever 143 is in its uppermost position (Fig. 1) and the block 291 stands idle at the extreme right. To change to distribution (Fig. 5) the lever 143 is moved to its lowermost position and then 130

the block 291 is shoved as far as possible to the left, which shoves the line in the tube 182 so that the forward type enters the turn-table. All the other changes necessary for 5 distribution occur automatically, consequent upon the movement of the lever 143. Restoring the lever and block to their first-mentioned positions, converts the machine to a composer. The ready change from assemblage to distribution, and vice versa, enables corrections to be very easily made, should errors occur during composing. Thus, if the operator discovers that he has struck the wrong character, it is only necessary for him to convert the machine to a distributor and to distribute the improper character to its receiving channel in the lower bank and then re-convert the machine to a composer and set the proper character. 10 15 20 25 30 35 40

It should be noted that the readily removable type banks of this machine not only enable convenient interchange of the assemblage and distribution cases, but enable the substitution of banks having other fonts of type—either a different face of type or a slightly different sized body. The same banks, gates and almost all of the mechanism may readily be employed, for example, for typewriter type of the two sizes commonly known as pica and élite. Assuming that the machine shown is for pica type, to change to élite it is only necessary to substitute a slightly thicker plate for the stop plate 65 so that, in assemblage, the next to the bottom type will not pass below the lower edge of the upper banks, and to substitute a slightly wider stop plate 196 at the turn-table so that the next to the forward type of the line being distributed will not pass into the turn-table.

Having thus described my invention, what I claim is:

1. In a typesetting and distributing machine, the combination, with interchangeable type banks down which type may slide by gravity, of mechanism for assembling type from the lower end of one bank and distributing type into the upper end of the other bank.
2. In a typesetting and distributing machine, the combination, with interchangeable type holders down which type may slide by gravity, of mechanism for assembling type from the lower end of one holder and distributing type into the upper end of the other holder, and a keyboard of finger keys connected with said mechanism.
3. The combination, with a pair of interchangeable type cases one mounted above the other, and mechanism for assembling type from the lower end of the upper case and distributing type into the upper end of the lower case.
4. The combination with a pair of interchangeable type cases one mounted above the

other, mechanism for assembling type from the lower end of the upper case and distributing type into the upper end of the lower case, and a keyboard of finger keys connected with said mechanism.

5. The combination of a pair of interchangeable type cases down which type may slide by gravity, means for assembling individual characters from the upper case and for distributing individual characters into the lower case, and means for transporting such characters from and to the respective cases.

6. The combination of a pair of bodily interchangeable type banks each having side by side channels down which type may slide by gravity, a series of devices for assembling individual characters from the respective channels of the upper bank and for distributing individual characters into the channels of the lower bank, and means for transporting such characters from and to said devices.

7. The combination of a pair of interchangeable type cases one above the other, and intermediate mechanism for assembling type from the lower end of the upper case and for distributing it into the upper end of the lower case.

8. The combination of a pair of interchangeable type cases one above the other, and intermediate oscillatory mechanisms adapted to be turned in one direction to assemble type from the lower end of the upper case and in the opposite direction to distribute it into the upper end of the lower case.

9. The combination of a pair of interchangeable type cases one above the other, intermediate mechanism for assembling type from the lower end of the upper case and for distributing it into the upper end of the lower case, and mechanism for moving such type laterally from the assemblage point and to the distributing point.

10. The combination of a pair of interchangeable type cases one above the other, intermediate mechanism for assembling type from the lower end of the upper case and for distributing it into the upper end of the lower case, finger keys and connections for operating said mechanism, and mechanism for moving type laterally from the assemblage point and to the distributing point.

11. The combination, with upper and lower type cases, of intermediate mechanism having one movement to assemble type from the lower end of the upper case and another movement to distribute type into the upper end of the lower case.

12. The combination, with upper and lower type cases, of intermediate mechanism having one movement to assemble type from the lower end of the upper case and another movement to distribute type into the upper

end of the lower case, and a keyboard of finger keys connected with said mechanism.

13. The combination, with upper and lower type cases, of intermediate mechanism having one movement to assemble type from the lower end of the upper case and another movement to distribute type into the upper end of the lower case, and means for laterally transporting type to and from such mechanism.

14. The combination, with upper and lower type cases, of intermediate mechanism having one movement to assemble type from the lower end of the upper case and another movement to distribute type into the upper end of the lower case, finger keys, representing different characters, mechanism connecting the same with the intermediate mechanism mentioned, and means for laterally transporting type.

15. The combination, with a pair of type cases, of intermediate mechanism adapted on one movement to receive a type from one case and by a return movement carry the type into delivery position, said mechanism also being adapted by one movement to receive type from a passageway and by a return movement deliver it to the other type case, a keyboard of finger keys corresponding to different characters, and mechanism connecting such finger keys with the intermediate mechanism referred to, whereby the down stroke of the keys operates the intermediate mechanism in one direction and the return stroke in the opposite direction.

16. The combination of a series of type repositories and a series of oscillatory gates adapted to be turned to distribute type into respective repositories, and means for transporting the type to such gates.

17. The combination of a series of type repositories, a series of oscillating gates adapted to be turned to distribute type into respective repositories, and means for transporting the type to such gates, and finger keys for operating the respective gates.

18. The combination of a type case having repositories down which type may pass by gravity, a series of oscillatory gates adjacent to the upper ends of the repositories, means for transporting type laterally to the desired gate, and means for oscillating said gates to divert the type into the respective repository.

19. The combination of a type case having repositories down which type may pass by gravity, a series of oscillatory gates adjacent to the upper ends of the repositories, means for transporting type laterally to the desired gate, and a set of finger key and connecting mechanism for oscillating said gates to divert the type into the respective repository.

20. The combination of a series of type repositories side by side, a series of gates,

each gate being provided with an open-ended groove and with another groove which is interrupted, and means for positioning the interrupted groove of a desired gate in alignment with open-ended grooves of other gates, said open-ended grooves thus providing a channel for the feeding of type to the interrupted groove.

21. The combination of a series of type repositories side by side, a series of movable gates, each gate being provided with an open-ended groove and with another groove which is interrupted, means for positioning the interrupted groove of a desired gate in alignment with open-ended grooves of other gates, and finger keys for operating said means.

22. The combination of a type case down which type may slide by gravity, a series of oscillatory gates above the type case, each gate being provided with an open-ended groove and an interrupted groove at an angle to the open-ended groove, said open-ended grooves normally aligning, and means for turning any desired gate to present its interrupted groove in alignment with the aligned grooves of the other gates.

23. The combination, with a type case, of a series of movable gates adjacent to the end of the case, each gate being provided with an open-ended groove and an interrupted groove, means for aligning the open-ended grooves, means for positioning any desired gate with its interrupted groove in alignment with the aligned grooves of the other gates, and means for transporting type through aligned grooves into an interrupted groove.

24. The combination of a series of movable gates each provided with an open-ended groove and an interrupted groove, and means for aligning the interrupted groove of any gate with open-ended grooves of a series of gates.

25. The combination of a series of movable gates each provided with an open-ended groove and an interrupted groove, means for aligning the interrupted groove of one gate with open-ended grooves of a series of gates, and means for transporting type through the aligned grooves of such series into the interrupted gate.

26. The combination of a series of movable gates each provided with an open-ended groove and an interrupted groove, a keyboard having keys corresponding to different characters, means operated by the keys for aligning the interrupted groove of the corresponding gate with open-ended grooves of a series of gates, and means for transporting type through the aligned grooves of such series into the interrupted gate.

27. The combination of a series of round gates mounted side by side, each gate being provided with a diametric open-ended

- groove and an interrupted groove at right angles to the diametric groove, and means for giving any of the gates a quarter turn to cause its interrupted groove to aline with the diametric grooves of the other gates.
28. The combination of a series of round gates mounted side by side, each gate being provided with a diametric open-ended groove and an interrupted groove at right angles to the diametric groove, means for giving one of the gates a quarter turn to cause its interrupted groove to aline with the diametric grooves of the other gates, and means for feeding type along the channel provided by such alined diametric grooves into the notch provided by the turned interrupted groove, and means for thereafter turning the gate with the last-mentioned groove to discharge the type therefrom.
29. The combination of a series of gates mounted side by side, each gate being provided with an open-ended groove and an interrupted groove, means for moving any of the gates to cause its interrupted groove to aline with the open-ended grooves of the other gates, mechanism for feeding type along the channel provided by alined grooves into the notch provided by the moved interrupted groove, means for thereafter moving the gate with the last-mentioned groove to discharge the type therefrom, and a series of finger keys for operating the means mentioned.
30. The combination of a series of round gates mounted side by side, each gate being provided with a diametric open-ended groove and a notch at right angles to the diametric groove, said gates having their diametric grooves normally alining but each being adapted to be given a quarter turn to cause its notch to aline with the diametric grooves of the other gates, means for feeding type along the channel provided by alined diametric grooves into the notch provided by a turned gate, a series of finger keys, and mechanism operated thereby for turning the respective gates first in one direction and then in the other.
31. The combination of two type cases, a series of intermediate gates, means on each gate for providing a continuous channel for transporting type, means for withdrawing type from one case and delivering it to the passageway provided by alined inactive gates, and means for receiving type through the passageway so provided and delivering it to the other type case.
32. The combination of two gravity type cases, one above the other, a series of intermediate gates, means on each gate for providing a continuous channel for transporting type, means for withdrawing type from the upper type case and delivering it to the passageway provided by alined inactive gates, and means for receiving type through

the passageway so provided and delivering it to the lower type case.

33. The combination of two gravity type cases, one above the other, a series of intermediate gates, means on each gate for providing a continuous channel for transporting type, means for withdrawing type from the upper type case and delivering it to the passageway provided by alined inactive gates, means for receiving type through the passageway so provided and delivering it to the lower type case, and a series of finger keys for operating the respective gates.

34. The combination of two gravity type cases, one above the other, a series of intermediate oscillatory gates, an open-ended groove on each gate for providing a continuous channel for transporting type, means for turning any gate to cause its groove to aline with a channel of the upper type case thus providing for withdrawing type from the upper type case and delivering it by a return movement of the gate to the passageway provided by alined grooves of inactive gates, means on each gate for receiving and holding type delivered through the passageway so provided and by a movement of the gate delivering it to the lower type case, and a series of finger keys for oscillating the respective gates.

35. The combination of a pair of gravity type cases, one above the other, a lateral series of round gates between the upper and lower cases, each gate having a diametric groove adapted to aline with others of such grooves to provide a lateral type channel, means operated by turning a gate for withdrawing type from the upper type case and delivering it to such lateral channel, and means operated by turning a gate for receiving type from the lateral channel and delivering it to the lower type case.

36. The combination of a pair of gravity type cases, one above the other, a lateral series of round gates between the upper and lower cases, each gate having a diametric groove adapted to aline with similar grooves in the other gates to provide a lateral type channel, means for withdrawing type from the upper type case and delivering it to such lateral type, and means for receiving type from the lateral channel and delivering it to the lower type case, and a keyboard of finger keys for operating said means.

37. The combination of a pair of type cases one above the other, a lateral series of gates mounted in horizontal alinement between the lower end of the upper type case and the upper end of the lower type case, each gate having an open-ended groove and a notch, means for causing the open-ended grooves normally to aline to provide a common type channel and the notches to aline with individual channels of one case, and means for alining the open-ended groove of

- any gate with a corresponding type channel of the other cases and for alining the notch of any gate with the series of open-ended grooves of the other gates.
- 5 38. The combination of a pair of type cases one above the other, a lateral series of round oscillatory gates mounted in horizontal alinement between the lower end of the upper type case and the upper end of 10 the lower type case, each gate having an open-ended groove and a notch at an angle to such groove, the open-ended grooves normally alining with each other to provide a common type channel and the notches normally alining with the individual channels of the lower case, and means for alining the open-ended groove of any gate with a corresponding type channel of the upper case and for alining the notch of any gate with the 15 series of open-ended grooves of the other gates.
39. The combination of a pair of type cases one above the other, a lateral series of round oscillatory gates mounted in horizontal alinement between the lower end of the upper type case and the upper end of the lower type case, each gate having an open-ended groove and a notch at an angle to such groove, the open-ended grooves 20 normally alining with each other to provide a common type channel and the notches normally alining with the individual channels of the lower case, and a series of finger keys corresponding to different characters, 25 and mechanism operated thereby and connected with the respective gates for alining the open-ended groove of any gate with a corresponding type channel of the upper case and for alining the notch of any gate 30 with the series of open-ended grooves of the other gates.
40. The combination with a plurality of type cases facing each other and each having rows of individual typeholders, and an intermediate type transfer mechanism adapted to coact first with the letters of one case and then with those of another.
41. The combination of two parallel type cases, and an intermediate type transfer mechanism adapted to coact on one side 50 while moving in one direction with one case and on the opposite side while moving in the opposite direction with the other case.
42. The combination of two type cases 55 facing each other, means for composing type from either case, and an intermediate transfer mechanism movable in one direction with reference to one case and the opposite direction with reference to the other.
- 60 43. The combination of two type cases facing each other, means for distributing type into either case, and an intermediate transfer mechanism moving in an orbit and having two oppositely moving portions between the two cases.
44. The combination of two type cases, means for distributing type into either case, finger keys for operating said means, and a type transfer mechanism common to both cases and moving past them in opposite directions.
45. The combination of two pairs of superimposed type cases, mechanism between the members of each pair for assembling type from the upper case or distributing it 70 into the lower case, and a transfer mechanism located between the two adapted to convey type to or from the intermediate mechanism of either pair.
46. The combination of two pairs of superimposed type cases, mechanisms between the members of each pair for assembling type from the upper case or distributing it 75 into the lower case, transfer mechanism located between the two adapted to convey type to or from the intermediate mechanism of either pair, a keyboard of finger keys, and mechanism operated thereby for controlling said intermediate mechanisms and said transfer mechanism.
47. The combination of two type cases each having channels for holding type, said cases being positioned one in front of the other, means providing a channel across each case along which the type may be propelled, and a U-shaped channel at one end 80 of the cases connecting the two channels mentioned.
48. The combination of two type cases each having channels for holding type 85 grooved on its opposite sides, said cases being positioned one in front of the other so that the type in the respective cases face each other, means for assembling type from the various channels of the two cases, there 90 being a channel in front of each case along which the type may be propelled, and a U-shaped channel at the end of the cases connecting the two channels mentioned.
49. The combination with a series of typeholders, of a series of individual gates adapted to coact with the respective holders or be turned to make a common delivery channel, and an endless belt to transfer type 95 in said delivery channel.
50. The combination of a series of type channels side by side, a series of individual gates for controlling the discharge thereof, each gate consisting of a head having a groove, said head being mounted to turn on an axis in one direction and then turn back again, a series of key levers for operating the respective gates, a universal bar and a notched bar operated thereby to stop the type.
51. The combination, with a pair of type cases parallel with each other and one in front of the other, and an endless belt having two oppositely moving portions between them for transporting type.

52. The combination of two type cases, one in front of the other and spaced from it, an endless belt traveling in an orbit between the cases, and mechanism for receiving type from any case and placing it in position for transportation by said belt. 59. The combination, with a pair of type cases parallel with each other and one in front of the other, an endless belt between them for transporting type, means for continuously driving the belt, and an escapement for controlling it. 70
53. The combination of two type cases, one in front of the other and spaced from it, an endless belt traveling between the cases, mechanism for receiving type from any case and placing it in position for transportation by said belt, and an arcual type channel at the ends of the cases substantially concentric of the belt at that point. 60. The combination with a series of type channels side by side, of a series of individual gates at the ends thereof, each gate being provided with a groove adapted to align with the corresponding channel or be turned to align with each other to form a delivery channel, and an endless belt adapted to transport the type along such delivery channel. 75
- 10 54. The combination, with a pair of type cases parallel with each other and one in front of the other, of an endless belt between them for transporting type, means providing a channel parallel with each type case, 20 and a U-shaped connecting portion adjacent to one end of the type cases. 61. The combination with a series of type channels side by side, of a series of individual gates at the ends thereof, each gate being provided with a groove adapted to align with the corresponding channel or be turned to align with each other to form a delivery channel, an endless belt adapted to transport the type along such channel, finger keys adapted to operate said gates, and a two-point escapement controlling the belt and operating to release it on the depression 80 and raising of any key. 85
- 25 55. The combination, with a pair of type cases parallel with each other and one in front of the other, of means providing a channel for carrying type having a straight portion parallel with each type case and a U-shaped connecting portion adjacent to one end of the type case, an endless belt having straight portions parallel with the 30 straight portions of the type channel, and a pulley concentric of the U-portion and carrying the belt. 62. The combination of two type cases, one in front of the other and spaced from it, an endless belt traveling in an orbit between the cases, and mechanism for stopping 95 at any case type delivered by said belt. 90
- 30 56. The combination of two type cases each having channels for holding type, said cases being positioned one in front of the other, a channel in front of each case along which the type may be propelled, a U-shaped channel at the end of the cases connecting the two channels mentioned, and an endless 40 belt adapted to travel parallel with the straight channels and the U-shaped channel. 63. The combination of two type cases, one in front of the other and spaced from it, an endless belt traveling between the cases, mechanism for receiving type from any case and placing it in position for transportation by said belt, and mechanism for stopping at any case type delivered by 100 said belt when moved in the opposite direction. 105
- 40 57. The combination of two type cases each having channels for holding type grooved on its opposite sides, said cases being positioned one in front of the other so that the type in the respective cases face each other, means for assembling type from the various channels of the two cases, there being a channel in front of each case along 50 which the type may be propelled, a U-shaped channel at the end of the cases connecting the two channels mentioned, and an endless belt adapted to travel parallel with the straight channels and the U-shaped channel. 64. The combination of type cases, a series of mechanisms formed to distribute type thereinto, an endless belt, and means for moving said belt first in one direction and then the other. 110
- 45 58. The combination of two type cases each facing each other, a series of oscillatory gates at the lower ends of the respective channels within the two cases, each gate being provided with a groove adapted to align 60 with the cases or turned to align with the other grooves of the other gates and thereby provide a common channel, and an endless belt between the cases adapted to feed type along such discharge channel. 65. The combination of type cases, a series of mechanisms formed to distribute type thereinto, finger keys for operating said mechanisms respectively, an endless belt, and means for moving said belt first in one direction and then the other to carry type to a distribution mechanism and then return for another type. 115
- 55 66. The combination of type cases, mechanism for assembling type from one case, 120 mechanism for distributing it into another, an endless belt, means for continuously rotating the belt to transfer type from the assemblage mechanism, and means for reciprocating the belt to transfer type to the 125 distribution mechanism. 120
- 60 67. The combination of type cases, a series of mechanisms operable for assembling

- type from one case and for distributing it into another, finger keys for operating said mechanisms respectively, an endless belt, means for continuously rotating the belt to transfer type from the mechanisms during assemblage, and means for reciprocating the belt to transfer type to the mechanisms during distribution.
68. The combination, with distribution mechanism, of an endless belt for transporting type thereto, and mechanism for causing the belt to reciprocate.
69. The combination, with distribution mechanism, of an endless belt for transporting type thereto, mechanism for causing the belt to reciprocate, and finger keys for controlling the distribution mechanism and the reciprocation of the belt.
70. The combination of assemblage and distribution mechanism, of an endless belt, means for giving the belt a continuous travel to carry type from the assemblage mechanism, and means for giving the belt a reciprocation to carry to the distributing mechanism.
71. The combination of assemblage and distribution mechanism, of an endless belt, means for giving the belt a continuous travel to carry type from the assemblage mechanism, means for giving the belt a reciprocation to carry to the distributing mechanism, finger keys for controlling the belt, and mechanism for changing the machine from assemblage to distribution.
72. The combination of assemblage and distribution mechanism, of an endless belt, means for giving the belt a continuous travel to carry type from the assemblage mechanism, means for giving the belt a reciprocation to carry to the distributing mechanism, an escapement mechanism operable to release the belt for assemblage, and finger keys for operating the escapement.
73. The combination of assemblage and distribution mechanism, of an endless belt, means for giving the belt a continuous travel to carry type from the assemblage mechanism, an escapement mechanism operable to release the belt for assemblage, and means for connecting the power with the belt in either of two directions for distribution, and finger keys for operating the escapement and the last-mentioned means.
74. The combination of distribution mechanism, conveying mechanism for carrying type thereto, a reversing clutch between the source of power and the conveying mechanism, and finger keys adapted on the down stroke to set the clutch in one direction and on the up stroke in the opposite direction.
75. The combination of assemblage and distribution mechanism, an endless belt adapted to shove type, a continuously rotating pulley tending to drive the belt in the assemblage direction, an escapement device for holding and releasing the belt, and a reversing clutch between the source of power and the belt pulley.
76. The combination of assemblage and distribution mechanism, conveying mechanism, an escapement device for holding and releasing the same, a reversing clutch between the source of power and the conveying mechanism, and finger keys adapted to actuate the escapement or the reversing clutch according to whether the machine is assembling or distributing.
77. The combination of assemblage and distribution mechanism, an endless belt adapted to shove type, a continuously rotating pulley tending to drive the belt in the assemblage direction, an escapement device for holding and releasing the belt, a reversing clutch between the source of power and the belt pulley, and finger keys adapted to actuate the escapement or the reversing clutch according to whether the machine is assembling or distributing.
78. The combination of assemblage and distribution mechanism, an endless belt adapted to shove type, a continuously rotating pulley tending to drive the belt in the assemblage direction, an escapement device for holding and releasing the belt, a reversing clutch between the source of power and the belt pulley, finger keys, mechanism actuated thereby and adapted to be connected with either the escapement or the reversing clutch, and a device for connecting said mechanism alternatively for assemblage or distribution.
79. The combination, with distribution devices, of an endless belt for transporting type to the same, a pulley by which said belt may be driven, a source of power adapted to continuously rotate, a reversing clutch between the source of power and the pulley comprising a disk rotating between the heads of a spool, and mechanism for shifting the spool to change the direction of rotation of the pulley.
80. The combination, with assemblage and distribution devices, of an endless belt for transporting type to or from the same, a pulley by which said belt may be driven, a source of power adapted to continuously rotate, a reversing clutch between the source of power and the pulley comprising a disk rotating between the heads of a spool, mechanism for shifting the spool to change the direction of rotation of the pulley, and an escapement device to control the belt for assemblage.
81. The combination, with assemblage and distribution devices, of an endless belt for transporting type to or from the same, a pulley by which said belt may be driven, a source of power adapted to continuously ro-

tate, a reversing clutch between the source of power and the pulley comprising a disk rotating between the heads of a spool, mechanism for shifting the spool to change the direction of rotation of the pulley, an escapement device to control the belt for assemblage, finger keys corresponding to the different characters, and means for causing said keys to operate the escapement or to shift the spool according to whether the machine is assembling or distributing.

82. The combination of a type case having a plurality of type channels, a row of oscillatory grooved type-receiving heads constituting composing devices coacting with the channels, said devices being adapted to serve more channels than there are devices, and means for changing the mutual presentation of the channels and devices to enable one device to serve a plurality of channels.

83. The combination of a shiftable type case having a plurality of channels, a series of assembling devices each consisting of a round grooved head mounted to turn on its axis, and means for shifting the type case to cause each device to serve a plurality of channels.

84. The combination of a shiftable type case having a plurality of channels, a series of assembling devices, each consisting of an oscillatory grooved head larger than the distance across a channel, means for shifting the type case to cause each device to serve a plurality of channels, and a keyboard having finger keys respectively connected with said devices and individually corresponding to a plurality of characters.

85. The combination of a type case having different channels for upper and lower case characters, a keyboard having keys common to both upper and lower case characters, a series of assemblage devices controlled by the keys respectively, and each consisting of an oscillatory grooved type-receiving head, and a shift mechanism for changing the presentation of the channels of the type cases to said devices.

86. The combination of a type case comprising a series of channels side by side down which type may slide by gravity, a series of gates below the channels adapted to receive type therefrom, each gate consisting of an oscillating grooved head and serving a plurality of channels, a keyboard having keys corresponding to a plurality of characters, mechanism between said keys and said gates for operating the latter, a shift key, and mechanism controlled thereby for shifting the type case relative to the gates.

87. The combination of a type bank comprising a series of bars held side by side and providing intermediate channels down which type may slide by gravity, a series of gates

coacting with the channels, one gate serving a plurality of channels, a keyboard having keys corresponding to a plurality of characters, mechanism between said keys and said gates for operating the latter, a shiftable plate on which the type bank is removable and mounted, and mechanism for shifting said plate.

88. The combination of a bank of type channels, a holder on which said bank is mounted and from which it is removable as a unit, mechanism for shifting said holder, a combined assemblage and distribution device co-acting with the channels of the type case and each device being adapted to serve a plurality of channels, finger keys for operating the respective devices and a shift key for actuating the shift mechanism.

89. The combination of type cases, devices for assembling type from the case, the type being adapted to fall by gravity from the case into said device, and means for shifting the case to carry it out of registration with said devices.

90. In a typesetting and distributing machine, the combination of a pair of cases one above the other, an intermediate device for assembling type from the upper case and distributing type into the lower case, the type being adapted to fall by gravity from the upper case into said device and from said device into the lower case and means for shifting one of said cases to carry it out of registration with said devices.

91. In a typesetting and distributing machine, the combination of a pair of cases one above the other, an intermediate device for assembling type from the upper case and distributing type into the lower case, the type being adapted to fall by gravity from the upper case into said device and from said device into the lower case, and means for shifting the upper case to carry it out of registration with said devices automatically when the machine is set for distribution, and mechanism for changing the machine from assemblage to distribution.

92. The combination of a pair of type cases one above the other having channels down which type may slide by gravity, a series of oscillatory gates between the cases, each gate having a groove to coact with the upper case during assemblage and having also means for presenting type to the distribution case, and means for shifting the upper case slightly with reference to the gates to carry the channels of the upper case out of registration with the grooves of the gates, preventing the type dropping into the gates at such time.

93. The combination of type cases one above the other, an intermediate series of gates adapted to assemble type from the channels of the upper case or distribute type

5 into the channels of the lower case, a lateral
transporting mechanism for carrying type
from and to said gates for assemblage and
distribution, mechanism for changing the
operation of the transporting device from
assemblage to distribution and vice versa,
and mechanism for shifting the upper case
out of registration with the gates consequent
upon the change from assemblage to distribution.

10 94. The combination of a type case into
which type may be distributed, means for
controlling the distribution, a channel leading
thereto, means for feeding type along
15 said channel, means for inverting each type
and finger keys for operating the distribution
means.

20 95. The combination of a type case into
which type may be distributed, a series of
gates for controlling the distribution, a
channel leading to the gates, means for feed-
ing type along said channel, and means for
inverting each type as it is fed.

25 96. The combination of a type case into
which type may be distributed, a series of
individual gates at the upper end of said
case, there being a horizontal channel along
which type may be fed to the gate corre-
sponding to the desired channel of the case,
30 means for propelling individual type from a
line to be distributed, and means for invert-
ing the individual type after it leaves the
line and before it reaches the gate.

35 97. The combination of a type case into
which type may be distributed, a series of
individual gates at the upper end of said
case, keys for operating the same, a hori-
zontal channel along which type may be fed to
the gate corresponding to the desired chan-
40 nel of the case, means for propelling type
along the channel from a line to be distrib-
uted, a turn-table for inverting the individ-
ual type, and means for giving the turn-

table a half rotation consequent upon the
actuation of the key.

45

98. In a typesetting and distributing ma-
chine, the combination of a case from which
type may be assembled, a case into which
type may be distributed, assemblage and dis-
tribution mechanism, means for transport-
ing type away from the assemblage mecha-
nism and for transporting type to the dis-
tribution mechanism, and means for invert-
ing the type when transferred to the distri-
bution mechanism.

50

99. The combination, with type cases, of
mechanism for assembling type for one case
and for distributing type into the other case,
means for feeding assembled type away
from the assemblage mechanism and for
feeding individual type toward the distrib-
uting mechanism, a turn-table adapted to in-
vert the individual type as they are fed to
distributing mechanism, means for chang-
ing the machine from an assembler to a dis-
tributer, and vice versa, and automatically
operating means for rendering the turn-
table inactive when the machine is compos-
ing and active when it is distributing.

60

100. The combination of a series of type
channels side by side, a series of individual
gates therefor each consisting of a head hav-
ing a groove and adapted to be given a quar-
ter turn to cause said groove to aline with
the corresponding channel or the grooves of
the various heads to aline with each other
and make a delivery channel, and a notched
bar extending crosswise of the gates and
adapted to stop the row of type when a gate
alines with a type channel.
